UNITED STATES PATENT OFFICE.

CHARLES J. PILLING, OF PHILADELPHIA, PENNSYLVANIA, ASSIGNOR TO
GEORGE P. PILLING AND CHARLES J. PILLING, OF SAME PLACE, (CO-
PARTNERS TRADING AS GEO. P. PILLING & SON.)

DESIGN FOR A BLANK FOR SPECULUM BLADES AND HANDLES.

SPECIFICATION forming part of Design No. 34,340, dated April 9, 1901.

Application filed February 9, 1901. Serial No. 46,747. Term of patent 7 years.

To all whom it may concern:

Be it known that I, CHARLES J. PILLING, a citizen of the United States, residing at the city of Philadelphia, State of Pennsylvania, have invented and produced a certain new and original Design for a Blank for a Speculum Blade and Handle, of which the following is a full, clear, and exact description, reference being had to the accompanying drawings, forming a part of this specification.

In the drawings, Figure 1 is a plan view, and Fig. 2 is a side view, of a blank.

My invention consists in the design, in novel external outline, planular shape, or configuration shown, of the blank from which the upper operating blade and handle of a bivalvular speculum is produced. The blank is of irregular outline. The side lines thereof, com-

mencing at the top of the blank, as shown, gradually converge and then diverge to form an enlarged portion, and then said side lines gradually converge by an irregular curve and join at the bottom of the blank. An aperture is formed in the enlarged portion.

I claim—

The design for a blank for a speculum blade and handle, substantially as shown and described.

In testimony whereof I have hereunto affixed my signature this 18th day of January, 1901.

CHARLES J. PILLING.
